US0D1050697S

(12) United States Design Patent (10) Patent No.: US D1,050,697 S
(45) Date of Patent: * Nov. 12, 2024

(54) SHOE

(71) Applicant: adidas AG, Herzogenaurach (DE)

(72) Inventors: Strahinja Spasic, Los Angeles, CA (US); Robert Stinchcomb, Chestertown, NY (US); Arnaud Sanjuan Roman, Brooklyn, NY (US); Baptiste Jacques Dany Tarenne, Fuerth (DE); Benjamin Alexander Thompsett, Nuremberg (DE)

(73) Assignee: adidas AG, Herzogenaurach (DE)

() Term: 15 Years

(21) Appl. No.: 29/871,063

(22) Filed: Feb. 10, 2023

(51) LOC (14) Cl. 02-04

(52) U.S. Cl.

USPC D2/962; D2/947

(57) CLAIM

The ornamental design for a shoe as shown and described.

DESCRIPTION

FIG. 1 is a top front isometric view of a shoe showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the shoe that form no part of the claimed design.

The dot-dash broken lines in the figures show boundaries that form no part of the claimed design.

1 Claim, 7 Drawing Sheets
